ATTORNEY

UNITED STATES PATENT OFFICE

165,847

ORNAMENTAL CHAIN

Christian F. Jager, Cranston, R. I., assignor to Armburst Chain Company, a corporation of Rhode Island

Application March 17, 1951, Serial No. 14,529

Term of patent 14 years

(Cl. D45—16)

To all whom it may concern:

Be it known that I, Christian F. Jager, a citizen of the United States, residing at Cranston, State of Rhode Island, have invented a new, original, and ornamental Design for an Ornamental Chain, of which the following is a specification, reference being had to the accompanying drawing, forming a part hereof.

Fig. 1 is a top plan view of a section of an ornamental chain embodying my new design, and

Fig. 2 is a side view thereof.

I claim:

The ornamental design for an ornamental chain, as shown.

CHRISTIAN F. JAGER.
